UNITED STATES PATENT OFFICE

AUGUSTO DINA, OF JERSEY CITY, NEW JERSEY, ASSIGNOR TO THE PRECISION MACHINE CO., INC., OF NEW YORK, N. Y., A CORPORATION OF NEW YORK

FILM-TRAPDOOR LOCK

Application filed September 5, 1925, Serial No. 54,618. Renewed June 27, 1929.

My invention relates to locking mechanisms for projectors.

The improvement herein described pertains to a locking mechanism adapted particularly for use with the film trap door of a motion picture projector, and more commonly known as a film trap door lock; the primary aim of the invention being to provide a locking mechanism which will serve positively to lock the film trap door closed.

It has been customary, in this particular connection, to secure the film trap door in locked position by spring means, which was unreliable and unsatisfactory, due to its non-positive locking action, and accordingly, was objected to by the underwriters. In order to permit the threading in of the film into position for projection, the door must be moved away from what is known as the head. The door should thereafter be brought lightly against the film in its threaded position, one reason for which is to hold the film from vibrating and to reduce possible conflagration should the automatic fire shutter fail to fall closed on ignition of the film. The ease with which the film may ignite, when passing through the projector, particularly in front of the shutter, is well known to those skilled in the art. Failure of the film to move usually results in combustion of the film, due to the intense heat. Automatic closing of the fire shutters is dependent upon this failure of movement of the film, but quite often the mechanical connection therebetween fails to release these shutters when the film stops. I find, therefore, that it is essential to safety to provide means which effectively minimize conflagration of the film by holding the film against the head under a positive locking action.

Briefly, my invention comprises an improved form of locking mechanism for a film trap door which is adapted positively to lock the door against the film when in position for projection, this lock being carried by an axially movable rod connecting the door by extending through the head. The door may be quickly brought to closed position against the film and locked, without the possibility of accidentally releasing. A spring pressed

pawl carried by a thumb piece at the end of the axially movable rod serves to snap into position against the head at one side, to hold the rod extended with the door effectively held locked against the head at the other side. An improved mounting is provided for the spring pressed pawl to compensate for any variation in the dimensions of the mechanism to which the lock is applied. I wish to emphasize the simplicity of the lock, its ability to be universally adapted and the quick and positive action obtained thereby when moved to locking position.

In order to apprise those skilled in the art how to practice and construct my invention, I shall now describe an embodiment thereof in connection with the accompanying drawings, which form a part hereof.

In the drawings:

Figure 1 is a front elevational view of that portion of the projector which embodies my invention;

Fig. 2 is a side elevational view of the same, illustrating partly in section the film trap door lock, and further illustrating the manner of readily attaching it to the door;

Fig. 3 is a vertical sectional view through the locking mechanism, illustrating the film trap door held positively locked in closed position;

Fig. 4 is a similar view having the film trap door released; and

Fig. 5 is a top view of the locking mechanism.

Referring more particularly to the drawings, 10 is the frame or head comprising that portion of the projector which carries the automatic fire shutter 11. This shutter 11 is vertically slidable, in a well known manner, in guides 12 formed on a plate 13 secured to the abutment or head 10. While it is not a part of the present invention, it may be mentioned that automatic releasing mechanism may be secured to this shutter, so that when the film stops moving past the shutter opening, the shutter immediately falls into closed position. This is accomplished by the links 14 and 15 being connected in a manner to allow shutter 11 to drop closed when the motion of the film is stopped.

On the opposite side of the head 10, a door 16 is provided to move against the former for the purpose of holding the film in threaded position, or position for projection between the head and the door. This is well known to those skilled in the art.

A hub 17 provided with a central opening to receive a bearing 18 may be formed on head 10 adjacent to the door 16. A rod 19, to which door 16 is fastened, passes centrally through bearing 18 and is permitted to have axial non-rotative movement therein so as to allow the door to be brought against the head, as shown in Figs. 2 and 3. The bearing 18 is enlarged at 20, in order to seat snugly in hub 17, and has an annular shoulder 21 thereon, preferably to space the door 16 from head 10, this space being provided for the film when threaded in the projector. The opposite end of bearing 18 may be reduced, as indicated at 22, to provide an annular groove 23 between the bearing and the hub. However, the central opening of the hub may be slightly larger at this point to insure the proper size annular groove 23.

The end of the rod 19 is internally threaded to receive a threaded stud 24. The threaded stud 24 is an extension of the member 26 and is formed with a collar 27. A thumb piece 28 is mounted upon and embraces the member 26 between the outer end of the latter and said collar 27, the collar serving as an abutment at one end for the thumb piece, while at the opposite end a cap nut 30 is threaded on the member 26 for preventing displacement of the thumb piece.

A pair of downwardly extending integral lugs 32 may be furnished on the lower side of thumb piece 28, these lugs being spaced apart to receive therebetween a spring pressed pivotally mounted pawl 33. A pin 35 threaded in at one side of these lugs, as shown in Fig. 1, serves as the mounting for pawl 33. A pocket 34 may be formed in the bottom of thumb piece 28 for the reception of one end of a compression spring 36. The opposite end of this spring seats in a similar pocket 37 in the pawl 33. The function of pawl 33 is to lock door 16 closed, as shown in Fig. 3, by having its inner end engage against the hub 17 as indicated at X in this Figure. That is to say, when the thumb piece 28 is engaged and pulled outwardly, the spring 36 presses the outer end of the pawl 33 downwardly in order to drop its inner end in front of the hub 17 for engagement therewith. A sleeve 38 is threaded upon the stud 24 and is brought tightly against collar 27. The locking pawl 33 presses against said sleeve and is retained thereby in the plane of hub 17. The locking pawl 33 is eccentrically adjustable on, that is, is loosely engaged with its fulcrum to compensate for any variation in the dimensions of the mechanism to which the lock is applied, say in the dimensions of the

door and head, or in the size of the hub and rod.

To open the door 16, the locking pawl 33 must be released by pulling upwardly on the outer end of the pawl against the tension of spring 36. This brings the locking pawl away from hub 17 at X to permit the rod to slide axially in the head and to move the door to open position. It will be noted that the outer surface of hub 17 is tapered slightly for allowing the pawl 33 to travel thereover, when the latter is released, and that the sleeve 38 moves into the annular groove 23.

From the foregoing description, it will be observed that the door is held positively locked against the head by virtue of the locking pawl 33 falling in front of the hub 17 and locking. Accidental release of the lock is difficult and is in fact prevented due to the spring 36 tending to hold the pawl pressed against the sleeve 38 and hub 17, and further, to the fact that this hub is provided with a tapered exterior surface over which the pawl must travel to open the door, and, as will be here seen, this movement must be accomplished with a positive force or an intentional release of the pawl.

It will be further observed that the locking mechanism, herein disclosed, is in the novel form of an interchangeable attachment, that is, the hub 17 and rod 19 are so constructed as to receive a standard door knob, if so desired. The manner of readily removing the locking mechanism has been clearly illustrated in Fig. 2. The ease of pulling the door to closed position, as well as the sure and positive action of the locking pawl 33 in locking position in front of the hub are important advantages of my invention. Once in this position it requires intentional release for the locking pawl 33 to move outwardly against the action of spring 36.

The invention is not to be limited to the detailed disclosure herein, as various modifications and other embodiments are possible, and will be apparent to those skilled in the art, without departing from the scope and spirit of the invention.

I claim:

1. A film trap door lock comprising a head and a film trap door movable thereagainst, a mechanical connection secured to said door and passing through said head, and spring actuated means at the outer end of said connection for positively engaging said head and thereby positively locking said door in closed position against said head.

2. In combination, a head, a door, and mechanism for positively locking said door in closed position against said head, said mechanism comprising a member having substantially axial movement in said head connected at one end to said door, and a locking element carried at the other end of said member tending normally to drop in front of said

- head to lock said member against said axial movement.
3. In combination, a head, a door, a hub on said head, an axially movable member passing through said hub, said member being secured at one end to said door, locking mechanism at the opposite end of said member for holding said door against said head, said locking mechanism including a releasable element having means tending to move it into a position against said head restraining the axial movement of said member. 70
4. In combination, a head, a door adapted to be positively locked in closed position when moved against said head, mechanism for locking said door closed, said mechanism comprising a movable member extending through said head and a spring pressed pawl mounted on said member, said pawl adapted to snap into position against said head to prevent the movement of said member and thereby lock said door closed. 75
5. In combination, a head, a door adapted to be locked in closed position against said head, means for moving said door to closed position and for locking the same therein, said means including an axially movable rod connecting to said door and extending through said head, and a spring pressed pawl pivotally mounted on said rod adapted automatically to snap into position against said head for preventing axial movement of said rod when said door is moved to closed position against said head by said rod. 80
- 35 6. In a locking mechanism for a film trap door, the combination of a head, means for moving said door to closed position against said head, said means comprising a movable rod seated in said head and connected to said door, and a locking pawl at the outer end of said rod for positively locking said door in closed position against said head. 85
7. In a locking mechanism for a film trap door, the combination of a head, means for moving said door to closed position against said head, said means comprising a movable rod seated in said head and connected to said door, and a locking pawl at the outer end of said rod for positively locking said door in closed position against said head, said pawl serving automatically to drop in front of said head to prevent inward movement of said rod. 90
- 55 8. In a locking mechanism for a film trap door, the combination of a head, means for moving said door to closed position against said head, said means comprising a movable rod extending within said head and connecting to said door, a gripping element on the outer end of said rod, and a latching element carried adjacent said gripping element for dropping into latching position against said head when said rod is moved outwardly from said head to close said door. 100
- 65 9. In a locking mechanism for a film trap door, the combination of a head, means for moving and locking said door in closed position against said head, said means comprising a rod passing through said head to said door, and detachably mounted locking mechanism at the outer end of said rod for positively locking said door in closed position. 105
10. In a locking mechanism for a film trap door, the combination of a head, a rod extending through said head for moving said door to closed position, an outwardly extending hub on said head through which said rod projects, and locking mechanism for preventing the movement of said rod in said head, said mechanism comprising a locking device adapted to drop in front of said hub. 110
11. In a locking mechanism for a film trap door, the combination of a head, a rod extending through said head for moving said door to closed position, a hub on said head through which said rod projects, and a locking pawl carried by said rod adapted to drop in front of said hub for preventing the movement of said rod in said head when said door is in closed position. 115
12. In a locking mechanism for a film trap door, the combination of a head, a rod extending through said head for moving said door to closed position, a hub on said head through which said rod projects, and a spring pressed pivotally mounted pawl at the outer end of said rod adapted to drop in front of said hub for preventing the movement of said rod in said head when said door is in closed position. 120
13. In a locking mechanism for a film trap door, the combination of a head, means for moving said door to closed position against said head, said means consisting of a rod connecting to said door and movably extending through said head, and means for positively locking said door against said head, said means including a pivotally mounted pawl disposed at the outer end of said rod adapted to drop in front of said head to prevent inward movement of said rod, said pawl being eccentrically adjustable at its pivotal mounting to compensate for variations in the dimensions of the parts of said mechanism. 125
14. In combination with a film trap door adapted to move to closed position against a head, and a rod connecting to said door and movably extending through said head, of locking mechanism for said door adapted positively to lock said door in closed position comprising a handle detachably connected to the outer end of said rod, and a spring pressed pawl arranged on said handle to lock said rod against inward movement. 130
15. In a device of the character described, an abutment and a trap door movable relatively thereto, means for moving said door connected thereto and extending to the opposite side of said abutment, a hub member through which said means is movable, and

means carried by said first mentioned means and positively engaging said hub to positively lock the door in one of its positions.

16. In a device of the character described, in combination, a film gate for a motion picture projector and a door adapted to be moved against said gate, of a rigid member supporting said door and passing through and slidale in said gate, said rigid member having a detachable handle portion on the end thereof opposite to said portion, a pawl member pivotally mounted on said handle, a hub member surrounding said rigid member and projecting from said film gate and disposed in a path to be engaged by said pawl when said handle is in a predetermined position.

In testimony whereof, I have hereunto signed my name.
